MEANS AND APPARATUS FOR THE GENERATION OF STEAM.

1,015,131.

Specification of Letters Patent.

Patented Jan. 16, 1912.

Application filed April 25, 1911. Serial No. 623,179.

To all whom it may concern:

Be it known that we, WILLIAM ARTHUR BONE, resident of the University, Leeds, in the county of York, England, professor of applied chemistry, JAMES WILLIAM WILSON, resident of Carlton Works, Arinley, Leeds, in the said county, gas-stove manufacturer, and CYRIL DOUGLAS McCOURT, resident of 13 Malwood road, Balham Hill, London, S. W., England, chemist, subjects of the King of Great Britain and Ireland, have invented new and useful Means and Apparatus for the Generation of Steam, of which the following is a specification.

This invention relates to means and apparatus for the generation of steam, and has for its object the utilization of the waste heat from coke ovens, furnaces or the like as a means for generating steam in boilers and the like.

In describing our invention in detail reference is made to the accompanying sheet of drawings similar letters indicating similar parts, in which—

Figure 1 represents a sectional elevation of an apparatus suited to our purpose. Fig. 2 represents a detail hereinafter referred to, and Figs. 3 and 4 represent further details hereinafter referred to.

In order that the nature of our invention may be clearly understood we will describe it in relation to the utilization of the waste heat resulting from the heating of coke ovens although it must be understood that we do not limit ourselves to such particular application but may employ our invention for the extraction of heat from other heated gaseous products.

We provide a boiler B of any suitable size and configuration such boiler being traversed by a number of tubes T of suitable dimensions such tubes being arranged horizontally, vertically or in any other convenient manner.

In the drawing we have shown a boiler B having horizontal tubes T of say 3 feet in length and 3 inches internal diameter, and a feed water heater J having tubes T' arranged vertically, the feed water heater being of any convenient size.

The tubes T and T' are packed with granular material G, such granules serving to assist in the transfer of heat, from the gases passing through the tubes, to the water sur-

rounding the tubes. The increased heat transfer appears to be due partly to the fact that the heated granules radiate heat to the walls of the tubes, and partly to the churning and baffling action which the fragments exercise on the flowing gas. The part played by radiation will depend on the temperature at which the hot gaseous products enter the tubes.

We have previously described and shown a boiler provided with tubes packed with granular material adapted to accelerate the combustion of an explosive mixture of suitable gases. The present invention differs therefrom in that no combustion need take place in the tubes and granular material the purpose of the tubes and granular material therein being to transfer the heat from hot gaseous products only to the water in the boiler.

In the boiler tubes T the granular material is retained by means of ferrules or plugs P of fireclay or the like at one end and by spiders or grids S at the other end the aperture P' in plug P being as large as possible consistent with retaining the granules in position. While granules of a somewhat larger size may be used in the front end (see Fig. 2) the size we prefer to adopt is one which will pass a sieve of one mesh to the linear inch but which will not pass a sieve of two meshes to the linear inch. Other sizes however may be employed, and we have found that as the size of the granules increases the resulting heat transfer per unit area of tube surface decreases, as does also the resistance to gaseous flow exercised by the granules. Hence if larger granules be employed it will be found desirable to increase the length of the boiler tubes. The granular material must be sufficiently refractory to stand the temperature produced in the hottest part of the tube, and in general may consist of firebrick crushed and meshed to the required size.

The tubes T' in the heater F do not require the plugs P, simple spiders or grids S' will answer the purpose. The water to the heater F is by preference caused to take a sinuous course around the tubes T', baffle plates C being arranged as shown, or in any other convenient or usual manner, the arrows indicating a suitable direction of flow of feed water.

The gaseous products are led from the usual tunnel or the like D to a firebrick or like chamber E provided with suitable means of access to the tubes and boiler at the boiler front. The rear ends of tubes T give admission into a chamber H in the nature of a smoke box having doors or the like H'. The chamber H communicates with chamber J having a door or doors in or at 5 J'; a passage, pipe or the like K leads from the exit end of the tubes T' of the heater F and in this passage is arranged a suitable fan or other exhausting appliance by which the hot gases are drawn through the boiler 10 and heater.

The feed water will be passed through the heater into the boiler in any ordinary or well known manner.

It will be seen that while a boiler adapted 20 as hereinbefore described may have a comparatively large diameter, the length thereof need only be comparatively small, but while we have mentioned tubes of 3 feet in length and 3 inches internal diameter, longer 25 or shorter tubes may be employed with an increase or decrease in the diameter thereof. When the said diameter of tubes is increased it will be found desirable to increase considerably the length thereof, and where these 30 larger and longer tubes are employed, and it is desired to spread the evaporation more uniformly along the length of tubes, such tubes may be provided with fire clay or like linings or sleeves adjacent to the ferrules P 35 and continue some distance along the tubes.

With regard to the packing of the tubes with granular refractory material, when such tubes are arranged vertically same may be evenly packed by merely dropping the 40 granules therin but where the tubes are arranged horizontally as in Fig. 1 this method will not apply. In order to pack the tubes evenly we use a special tool, (see Figs. 3 and 4) comprising a disk L having fingers or 45 projections L' near its periphery the disk being mounted on a convenient handle. The granular material is placed in the tube and pushed home by the disk, a rotatory or semi-rotatory motion being given thereto. 50 This action is continued until the tube is filled.

Instead of irregular fragments being employed as a granular packing for the tubes fire clay balls or the like of a suitable size 55 may be employed.

What we claim as our invention is:—

1. In water heaters, a heater inlet chamber adapted to receive hot gases, a series of substantially vertically arranged heater 60 tubes communicating with said heater inlet chamber, an exhaust passage communicating with the discharge end of said heater tubes and an exhaust fan connected with said exhaust passage to draw the cooled 65 gases therethrough and down through said

heater tubes, each of said heater tubes being packed with granular refractory material of between about one-half and one inch mesh and means including a series of horizontal baffles to pass the feed water 70 through said heater around said tubes in a sinuous upward direction.

2. In water heaters, a heater inlet chamber adapted to receive hot gases, a series of substantially vertically arranged heater 75 tubes communicating with said heater inlet chamber, an exhaust passage communicating with the discharge end of said heater tubes and an exhaust device connected with said exhaust passage to draw the cooled 80 gases therethrough and down through said heater tubes, each of said heater tubes being packed with granular material of between about one-half and one inch mesh and means to pass the water through said heater 85 around said tubes in a sinuous upward direction.

3. In water heaters, a heater inlet chamber adapted to receive hot gases, a series of substantially vertically arranged heater 90 tubes communicating with said heater inlet chamber, an exhaust passage communicating with the discharge end of said heater tubes and an exhaust device connected with said exhaust passage to draw the cooled 95 gases therethrough and down through said heater tubes, each of said heater tubes being packed with granular material and means to pass the feed water through said heater 100 around said tubes in a sinuous upward direction.

4. In water heaters, a heater inlet chamber adapted to receive hot combustion gases, a series of heater tubes communicating with said heater inlet chamber, an exhaust passage 105 communicating with the discharge end of said water tubes and an exhaust device connected with said exhaust passage to draw the cooled gases therethrough and through said heater tubes, each of said 110 heater tubes being packed with granular material and means to pass the water through said heater around said tubes.

5. In water heaters, a heater inlet chamber, means to supply hot combustion gases 115 thereto, a series of heater tubes communicating with said heater inlet chamber to receive said gases therefrom, an exhaust passage communicating with the discharge end of said heater tubes, each of said heater 120 tubes being packed with granular material and means to supply water around said tubes.

6. In water heaters, a heater inlet chamber, means to supply hot combustion gases 125 thereto, a series of heater tubes communicating with said heater inlet chamber to receive said gases therefrom, an exhaust passage communicating with the discharge end of said heater tubes, each of said heater 130

tubes being packed with granular refractory material of between about one-half and one inch mesh and means to supply water around said tubes.

5. 7. In water heaters, a heater inlet chamber, means to supply hot gases thereto, a series of heater tubes communicating with said heater inlet chamber to receive said gases therefrom, each of said heater tubes containing granular material of between about one-half and one inch mesh and means to supply water around said tubes.

10. 8. In water heaters, a heater inlet chamber, means to supply hot gases thereto, a series of heater tubes communicating with said heater inlet chamber to receive said gases therefrom, said heater tubes containing throughout part of their length non-combustible material and means to supply water around said tubes.

15. 9. In water heaters, a heater inlet chamber adapted to receive hot combustion gases, a series of heater tubes communicating with said heater inlet chamber, each of said heater tubes containing granular material

and means to pass the water through said heater around said tubes.

10. In water heaters, a heater inlet chamber adapted to receive hot gases, a series of substantially vertically arranged heater tubes communicating with said heater inlet chamber, an exhaust passage communicating with the discharge end of said heater tubes and an exhaust device connected with said exhaust passage to draw the 30 cooled gases therethrough and down through said heater tubes, each of said heater tubes containing granular material and means to pass the feed water through 35 said heater around said tubes in a sinuous 40 upward direction.

In witness whereof we have hereunto set our hands, in the presence of two witnesses.

WILLIAM ARTHUR BONE.

JAMES WILLIAM WILSON.

CYRIL DOUGLAS McCOURT.
